UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

PICKER-CHECK FOR LOOMS.

1,074,756.

Specification of Letters Patent.

Patented Oct. 7, 1913.

Application filed July 10, 1911. Serial No. 637,596.

To all whom it may concern:

Be it known that I, EDWARD S. STIMPSON, of Hopedale, in the county of Worcester and State of Massachusetts, have invented certain new and useful Improvements in Picker-Checks for Looms, of which the following is a specification.

The present invention consists in certain improvements upon the character of picker check shown, for example, in the United States Letters Patent of Timothy Mooney, No. 780,485, January 17, 1905, and the special object of the present invention is to utilize the principle of such picker checks in automatic weft-replenishing looms of the type in which the replenishment of weft is effected by ejecting downwardly a spent weft-carrier in the shuttle through a slot in the lay at the replenishing end thereof.

The present improvements are illustrated in the accompanying drawings, in which— Figure 1, is a plan view of the lay of a weft-replenishing loom, the central portion of the lay being broken away. Fig. 2, is a front view of the parts of the lay shown in Fig. 1. Fig. 3, is an enlarged horizontal section in the plane indicated by the line 3—3 in Fig. 2. Fig. 4, is a vertical cross-section in the plane indicated by the line 4—4 in Fig. 1.

A, is the lay, having a slot *a*, at its replenishing end for the downward discharge of the spent weft-carrier from the shuttle when the shuttle is at that end of the lay.

B, B, are the pickers and C, C, are the picker sticks. These parts are such as are ordinarily employed in the well-known Northrop loom, which is illustrated, for example, in United States Letters Patent of James H. Northrop, No. 529,940, November 27, 1894.

D, and E, are the picker checks at the opposite ends of the lay. Each picker check is a strap, preferably of leather, and is fastened at the rear of the lay, passes across the end of the lay above the same and outside of and in line with the neighboring picker B, and the two picker checks are operatively connected with each other at their ends which are located in front of the lay.

It is customary, as shown, for instance, in the Mooney patent, to have a single strap extending entirely across the loom and supplying checks for both pickers. This has

been found to be inconvenient in automatic weft-replenishing looms, particularly in those of the "feeler" type wherein the replenishment is automatically effected while the running weft still remains intact, the replenishing mechanism being called into action by means of a "feeler" which passes through a slot in the shuttle-box at the end of the lay remote from the replenishing mechanism and through a slot in the wall of the shuttle and into contact with the weft within the shuttle, the replenishing mechanism acting when the weft within the shuttle is reduced to a definite minimum. Such a feeler loom is shown, for example, in United States Letters Patent of William Haynes, No. 685,236, October 22, 1901. In the present drawings the front-plate F, is shown provided with a slot *b*, and the shuttle G, is shown with a slot *c*, for the reception of the feeler. Picker check straps such as have heretofore been in use get in the way of the feeler and also in the way of the weft-carriers ejected downward through the slot *a*, in the lay at its replenishing side.

The principal object of the present invention is so to connect the two picker checks D, and E, so that the feeler slot *b*, and the weft-carrier discharge slot *a*, shall be wholly unobstructed by said connection.

The picker check D, is connected at its front end to the upper end of a lever H, which is centrally pivoted at *d*, to a bracket *e*, fastened to the front side of the lay below the shuttle-box. This lever H, is entirely outside of the feeler slot D, and extends below the bottom of the lay. Likewise the picker check E, at the replenishing end of the lay is connected at its front end with a lever I, centrally pivoted at *b*, to a bracket *g*, fastened to the front side of the lay. This lever I is wholly away from the weft-carrier discharge slot *a* and it extends below the bottom of the lay. The lower ends of the two levers H, and I, are connected by a thrust rod J, which extends lengthwise of the lay just below the bottom thereof. This rod (which is a stout metal wire) has an outwardly projecting bend *h*, opposite the inner end of the slot *a*, and the portion *i*, of the rod which extends in front of the slot *a*, is advanced sufficiently far so as not to interfere with the free drop of the weft-carriers falling through said slot. It will

be noted that the bracket *g*, extends to a greater distance forward of the lay than does the bracket *e*, thus allowing for the forwardly extending location of the end *i*, of the rod *J*. By reason of this construction the two picker checks are operatively connected so that they do not interfere with any of the functions of the lay of an automatic feeler weft-replenishing loom.

10 When the shuttle *G*, is thrown into the shuttle-box at the left-hand end of the lay (as shown in Fig. 1) it encounters the picker *B*, which in turn encounters the check *D*, and is thereby cushioned. The outward movement of the check *D*, caused by the impact of the picker swings the upper end of the lever *H*, outwardly and its lower end inwardly. The rod *J*, receives the thrust of the lower end of the lever *H*, and is hence moved lengthwise of the lay and toward its other end. Accordingly, the lower end of the lever *I*, is moved outwardly and its upper end is moved inwardly, thereby moving inwardly the check *E*, so that it crosses the picker slot *m*, at the right-hand end of the lay ready to cushion the corresponding picker when it is driven outwardly by the shuttle thrown in the opposite direction.

25 At each flight of the shuttle one picker check acts as a picker cushion and the other is put into cushioning position.

30 Each picker check is adjustably clamped at its rear end to the rear of the lay and as this adjustable connection is the same for both checks it will suffice to describe that of the check *D*. As shown in Fig. 3, the check has a longitudinal slot *s*, through which extends a clamping bolt *t*, carried by a bracket *w*, fixed to the lay and the rear end of the

check is clamped in its adjusted position by 40 means of a clamping nut *x*, and washer *y*.

I claim:

1. An automatic feeler weft-replenishing loom having, in combination, a lay having a weft-carrier discharge slot at one end and an apertured front plate at its other end; a picker check at each end of the lay fastened at its rear end at the back of the lay, extending across the outer end of the lay in the path of the neighboring picker, and thence to the front of the lay; two vertically disposed levers centrally pivoted at the front of the lay and connected at their upper ends respectively to said picker checks, and a thrust rod connecting said levers at their lower ends, said thrust rod extending beneath both shuttle-boxes and extending forward of the lay opposite the weft-carrier discharge slot therein.

2. An automatic feeler weft-replenishing loom having, in combination, a lay having a weft-carrier discharge slot at one end and an apertured front plate at its other end; a picker check at each end of the lay fastened at one end to the lay, and extending across the outer end of the lay in the path of the neighboring picker; two levers pivotally mounted on the lay each connected at one end to one of said picker checks, and a thrust rod connecting said levers at their other ends.

In witness whereof, I have hereunto signed my name in the presence of two subscribing witnesses.

EDWARD S. STIMPSON.
